QUICK-RELEASE FASTENER

Frank Bernard Harley, Camberley, England, assignor to Aerolex Limited, Camberley, England

Application June 6, 1949, Serial No. 97,451
In Great Britain October 29, 1948

18 Claims. (Cl. 24—230)

1

This invention relates to quick-release fasteners for use in releasably holding two parts together against relative sliding movement.

According to the present invention one part of a quick-release fastener comprises a catch which is formed with an abutment surface while the other part, which is formed slidably to receive the catch part, is fitted with a locking pin formed with a locking surface extending transversely to the line of sliding movement of the catch and with a backed-off releasing surface, and the pin is mounted for movement against return spring means in a rotary sense to carry its backed-off surface to a freeing position in which it is opposed to the abutment on the catch and in a longitudinal transverse sense to move clear of the abutment on the catch part.

When the pin is in its locking position, its locking surface extends transversely to the action of the load to which the fastener is connected so that the force tending to move the two parts of the catch apart, acts in the direction normal to the locking surface which thus affords a positive lock: by moving the pin rotatably, the backed-off surface is carried round to be presented to the abutment on the catch part and as a result the force acts either to assist or to force of itself the longitudinal movement of the pin to clear the abutment, the pin being returned automatically by the spring means to its locking position.

The locking pin would usually be of circular cross-section or at least the operative face would be part-circular formed, the curvature being effected about the axis of rotary movement: as the load exerted on the pin is normal to its locking surface, this arrangement enables the pin to be moved rotatably without difficulty: in most cases, the pin would be arranged for operation by an operating member which when turned to move the pin rotatably also moves the pin longitudinally by cam action.

The invention is illustrated in the accompanying drawings in which Figure 1 is a side elevation of a locking device as it would be fitted in for example a safety belt arrangement for use by the passengers of aircraft, Figure 2 a plan view of Figure 1, and Figures 3 and 4 are detail views of the locking part of the device: Figure 5 is a side elevation of a modification and Figure 6 is a sectional elevation of a further modification.

Referring first to Figures 1-4, the quick release connector comprises two parts 1, 2 of which the part 1 forms the catch part which is formed by a flat plate having an abutment surface 3 which

2

is constituted by the wall of a hole formed in that part 1, this part 1 being formed also with an opening 4 to enable one end of a strap 5 to be secured by looping and sewing at 6 to that part.

5 The other part 2 is in the form of a holder comprised by a shallow sheath part 7, into which the flat plate 1 can be fitted from one end, this sheath having at the end opposite the open end of the sheath openings 8 to receive one end of a 10 second strap 9 which is secured against withdrawal by rolling or doubling the strap 9 as indicated at 10, this loop in the strap enabling the strap to be adjusted by being pulled through the openings 8.

15 The part 2 has mounted in it a locking pin 11 which is movable rotatably and is slidably longitudinally of itself and transversely to the line of movement of the catch plate 1 into the holder 2, the pin being mounted for such movement in a 20 sleeve extension 12 of the sheath 7: the lower end of the pin is formed with a backed-off surface 13 and the pin is acted on by a spring 14 which biases the pin both against longitudinal and rotary movement from the locking position shown in Figures 3 and 4 in which the pin extends at its lower end to lie across the receiving recess of the sheath and with its backed-off surface 13 facing the receiving mouth 15 of the sheath.

25 The pin has secured to its outer end an operating component which can be in the form of a disc 16 as indicated in Figures 1-4 or in the form of a lever 17, the disc or the lever being mounted for rotary movement on the sleeve extension 12 of the sheath 7.

30 When the parts are in the locking position shown in Figure 3 and 4, i. e. with the pin 11 extending across the opening of the sheath 7 and with the pin turned to present its backed-off end 13 towards the mouth 15, if the plate part 1 is 35 fitted into the sheath, its leading end engages the backed-off end 13 of the pin and consequently the continued movement of the plate cams or lifts the pin until against the action of the spring 14 when the abutment edge 3 in the 40 plate 1 passes the pin, the pin is caused to spring into the opening and so to lock the plate 1 against withdrawal.

45 In the now locked portion of the plate 1, any loading exerted on the straps 5, 9 tending to pull the plate 1 out of the sheath 7 is resisted by the surface of the pin 11: as the pin extends transversely to the sliding movement of the plate, the loading reaction between the surface of the pin 55 and the abutment 3 is normal to that surface

which by being guided by the sleeve extension 12 is well adapted to withstand that reaction since it does not tend to displace the pin.

The locking surface of the pin is not only arranged transversely to the sliding movement of the plate: it is also formed by the curved surface of the pin which is cylindrical in cross-section. By this arrangement, the pin can readily be turned about its axis by turning the disc 16 or the lever 17. Such turning movement carries the backed-off end 13 of the pin through 180° from the position shown in Figure 4 to the position in which the backed-off surface is facing the abutment surface 3 on the plate 1. Any load on the straps 5, 9 is now applied to the backed-off surface which causes the pin 11 to be cammed to move longitudinally until finally the lower end of the pin is clear of the plate 1 which can now be completely withdrawn from the sheath 7.

Thus, by a simple turning movement of the disc 16, the connector can be freed, the freeing action being the greater, the greater is the loading to which the connector is subjected.

The lever 17 can be employed in those cases where a provision has to be made to release trapped occupants of a vehicle from outside the vehicle: the lever 17 could be engaged readily by a hooked component such as a walking-stick for example and to facilitate such use, the lever can be formed with a projection 18 to enable the hook to obtain the necessary purchase. To move the pin 11 into freeing position, it is necessary deliberately to turn the pin against its restoring bias of the spring 14 but this is an operation which can be effected by one hand of the user. This renders the invention especially useful as the quick-release fastening for safety belts used on aircraft and also for parachute harness where the ability to release the connection quickly and with one hand is an important consideration.

In the arrangement as so far described, the release operation requires the operator merely to turn the pin 11: it is however preferred to arrange that the turning of the pin 11 also effects a longitudinal movement of the pin by a positive cam action: this is effected in the arrangement shown in Figures 3 and 4 by providing a sleeve extension 19 to the disc 16 and forming the lower edge with a cam surface 20 which is held by the spring 14 against a reaction peg 21 secured to the sleeve 12: as the disc is turned to present the backed-off surface 13 to the abutment surface 3, the cam 20 and peg 21 co-operate to lift the pin to clear the plate 1: this operation overcomes any tendency for the pin 11 to be sluggish in freeing the catch plate 1.

In the arrangement shown in Figures 3 and 4 the disc 16 is fast with the locking pin 11 and it is therefore possible to effect release by moving the disc (and with it the pin) axially until the pin clears the catch plate: this may be undesirable in certain uses and another arrangement is proposed which ensures that release can be effected only by turning the disc.

This is illustrated in Figure 5 in which the disc 16 is provided with a pin 22 which enters a box or positive cam groove 23 in the sleeve 12 on the sheath 7; thus it is only by turning the disc that it can be moved axially through the action of the cam which however prevents the disc from being moved by direct end pressure.

A somewhat similar arrangement is shown in Figure 6 in which however the locking pin 11 is not secured to the disc 16 but it is connected to

it through a lost motion which enables the axial movement of the disc to be transmitted to the pin 11 to move it clear of the catch part 1 while yet allowing the pin 11 to move out against the spring 14 with respect to the disc 16 when the catch plate 1 is forced into locked position: the lost motion device is afforded by providing the outer end of the locking pin 11 with a head 24 which is located in a counter-bore in the disc 16, the wall of the counter-bore engaging under the head 24 to move it axially by operation of the disc and the head leaving that wall when the pin is forced out by the catch part 1.

The pin 11 is mounted in the disc 16 to turn with it so that when the disc is turned the backed-off surface of the pin is caused correspondingly to be turned this being effected by providing the pin 11 with a key 25 slidable in a key-way 26 in a sleeve extension 27 of the disc. The single spring 14 can be replaced by two separate springs, one for applying the longitudinal bias and the other for the rotary bias to the locking pin.

It is to be understood that while some of the more important uses of the quick-release fastening of this invention have been referred to, the invention is capable of general application as a quick-release fastener.

What I claim is:

1. A quick-release connector comprising a catch component having an abutment surface, a locking component which slidably receives the catch component, and a locking pin having a locking surface and a backed-off releasing surface, the locking pin being mounted in the locking component for longitudinal movement transverse to the sliding movement of the catch component and for rotary movement about its own axis, the longitudinal movement carrying the locking surface from a normal position opposed to the abutment surface to a freeing position clear of that surface and the rotary movement carrying the backed-off surface from a normal position to a freeing position opposed to and acted upon by the abutment surface to urge the locking component to freeing position, spring means urging the locking pin to its normal position, and a cam device coaxial with said locking pin and having mechanical connection therewith to effect movement thereof transverse to sliding movement of said catch component upon rotary movement of said locking pin.

2. A quick-release connector comprising a catch plate formed with an abutment surface, a sheath component receiving the catch plate, a locking pin mounted in the sheath component for rotary movement about its own axis and for longitudinal movement transverse to the sliding movement of the catch plate, the locking pin having a locking surface which is moved by the longitudinal movement from its normal position opposed to the abutment surface to a release position clear of the abutment surface and the locking pin having a backed-off releasing surface which is carried by the rotary movement from a normal position remote from the abutment surface to a freeing position opposed to and acted upon by that surface to urge the locking pin to freeing position, and combined compression and torsion spring means biasing the locking pin longitudinally and rotatably to its normal position.

3. A quick release connector comprising a catch component having an abutment surface, a locking component which slidably receives the

catch component, and a locking pin having a locking surface and a backed-off releasing surface, the locking pin being mounted in the locking component for longitudinal movement transverse to the sliding movement of the catch component and for rotary movement about its own axis, the longitudinal movement carrying the locking surface from a normal position opposed to the abutment surface to a freeing position clear of that surface and the rotary movement carrying the backed-off surface from a normal position to a freeing position opposed to and acted upon by the abutment surface to urge the pin to freeing position, an operating component to rotate the locking pin from normal to release position, and a cam device coaxial with said locking pin and having mechanical connection therewith to effect movement of said locking pin transverse to sliding movement of said catch component upon rotary movement of said locking pin.

4. A quick release connector comprising a catch plate formed with an abutment surface, a sheath component receiving the catch plate, a locking pin mounted in the sheath component for rotary movement about its own axis and for longitudinal movement transverse to the sliding movement of the catch plate, the locking pin having a locking surface which is moved by the longitudinal movement from its normal position opposed to the abutment surface to a release position clear of the abutment surface and the locking pin having a backed-off releasing surface which is carried by the rotary movement from a normal position remote from the abutment surface to a freeing position opposed to and acted upon by that surface to urge the pin to freeing position, an operating component to rotate the locking pin from normal to release position, and a cam coaxial with and having mechanical connection with said locking pin to effect movement thereof transverse to the sliding movement of said catch plate upon rotary movement of said locking pin.

5. A quick release connector comprising a catch component having an abutment surface, a locking component which slidably receives the catch component, and a locking pin having a locking surface and a backed-off releasing surface, the locking pin being mounted in the locking component for turning movement and for longitudinal movement transverse to the sliding movement of the catch component, the longitudinal movement carrying the locking surface from a normal position opposed to the abutment surface to a freeing position clear of that surface and the turning movement carrying the backed-off surface from a normal position to a freeing position in which it is opposed to the abutment surface to urge the pin to slide to its freeing position, an operating component to turn the locking pin, and a cam device coaxial with said locking pin and operative upon rotation of said locking pin to move it longitudinally from normal to release position.

6. A quick release connector comprising a catch plate formed with an abutment surface, a sheath component receiving the catch plate, a locking pin mounted in the sheath component for turning movement and for longitudinal movement transverse to the sliding movement of the catch plate, the locking pin having a locking surface which is moved by the longitudinal movement from its normal position opposed to the abutment surface to a release position clear of the abutment

surface and the locking pin having a backed-off releasing surface which is carried by the turning movement from a normal position remote from the abutment surface to a freeing position opposed to that surface, an operating component to turn the locking pin to present the backed-off surface to the catch plate, and a cam device coaxial with said locking pin and operative to move the pin longitudinally from normal to release position upon the turning of said pin.

7. A quick release connector comprising a catch component having an abutment surface, a locking component which slidably receives the catch component, and a locking pin having a locking surface and a backed-off releasing surface, the locking pin being mounted in the locking component for longitudinal movement transverse to the sliding movement of the catch component and for turning movement, the longitudinal movement carrying the locking surface from a normal position opposed to the abutment surface to a freeing position clear of that surface and the turning movement carrying the backed-off surface from a normal position to a freeing position opposed to and acted upon by the abutment surface to be urged to slide to freeing position, an operating component secured to the locking pin to move the backed-off surface from its normal position to its freeing position and cam mechanism, including a cam coaxial with said locking pin, causing turning movement of the pin to effect also longitudinal movement of the pin from locking position.

8. A quick release connector comprising a catch plate formed with an abutment surface, a sheath component receiving the catch plate, a locking pin mounted in the sheath component for turning movement and for longitudinal movement transverse to the sliding movement of the catch plate, the locking pin having a locking surface which is moved by the longitudinal movement from its normal position opposed to the abutment surface to a release position clear of the abutment surface and the locking pin having also a backed-off releasing surface which is carried by the turning movement from a normal position remote from the abutment surface to a freeing position opposed to and acted upon by that surface to be urged to move longitudinally to release position, an operating component secured to the locking pin to turn the backed-off surface from its normal position to its freeing position and cam mechanism, including a cam coaxial with said locking pin, to cause the pin to be also longitudinally moved from locking position as it is turned.

9. A quick release connector comprising a catch component, a second component detachably receiving the catch component, and a locking component having a locking surface which is slideable longitudinally into and out of a normal position in the path of the catch component and which is formed with a sloping release surface, and means to rotate the locking component about its axis to carry the release surface from a normal position remote from the catch component to a releasing position opposed to that component, spring means urging the locking component to its normal position, and a cam device coaxial with said locking component and operative upon rotation thereof for moving it out of the path of said catch component.

10. A quick release connector comprising a catch component, a second component detachably

receiving the catch component, a locking component mounted in the second component to slide transversely to the movement of the catch component and to turn on its own axis, the locking component having a locking surface parallel with its axis of turning movement and curved about that axis and the locking component having also a releasing surface which is backed-off from the locking surface, spring means biasing the locking pin to a normal position with the locking surface opposed to the catch component and with the backed-off surface remote from the catch component, an operating component mounted to move rotatably about the axis of the locking component, cam means to cause the rotary movement of the operating component to be effected also by longitudinal movement thereof in at least one direction, means connecting the locking pin to the operating member for turning movement therewith, and means to transmit longitudinal movement of the operating member to the locking pin while allowing the pin to move longitudinally independently of the operating member.

11. A quick release connector comprising a catch member, a receiving member slidably to receive the catch member, a locking pin of circular cross-section slidable axially in the receiving member into and out of the path of the catch member, the lower end of the pin being backed-off, spring means biasing the lower end of the pin into the path of the catch member and with its backed-off surface facing away from the catch member, and an operating member connected to the pin to turn it to present the backed-off surface to the catch member.

12. A quick release connector comprising a catch member, a receiving member slidably to receive the catch member, a locking pin of circular cross-section slidable axially in the receiving member into and out of the path of the catch member, the lower end of the pin being backed-off, spring means biasing the lower end of the pin into the path of the catch member and with its backed-off surface facing away from the catch member, an operating member for turning the pin to present the backed-off surface to the catch member, and cam means to cause the locking pin to move longitudinally when it is turned by the operating member.

13. A quick release connector comprising a catch member, a receiving member slidably to receive the catch member, a locking pin of circular cross-section slidable axially in the receiving member into and out of the path of the catch member, the lower end of the pin being backed-off, spring means biasing the lower end of the pin into the path of the catch member and with its backed-off surface facing away from the catch member, an operating member to turn the pin to present the backed-off surface to the catch member and cam means holding the locking pin against longitudinal movement except when the pin is turned by the operating component.

14. A quick release connector comprising a catch member, a receiving member slidably to receive the catch member, a locking pin of circular cross-section slidable axially in the receiving member into and out of the path of the catch member, the lower end of the pin being backed-off, spring means biasing the lower end of the pin into the path of the catch member and with its backed-off surface facing away from the catch member, an operating member to turn the pin to present the backed-off surface to the catch member, cam means to cause the operat-

ing member to move longitudinally when it is turned, means connecting the locking pin for turning and longitudinal movement with the operating member and for permitting the pin to move longitudinally independently of the operating member.

15. A quick-release connector comprising a catch component having an abutment surface, a locking component which slidably receives the catch component, said locking component having a cylindrical locking pin mounted for longitudinal movement transverse to the sliding movement of said catch component and for rotary movement about its own axis, one end of said locking pin being transversely inclined to provide a locking surface and a backed-off releasing surface, spring means normally urging said pin to its locking position, the other end of said pin having fixed thereto an operating element adapted to positively rotate the pin to and from locking position, and a cam device coaxial with said locking pin to simultaneously move the pin longitudinally to project or retract the inclined end thereof when said pin is rotated.

25. 16. A quick release connector comprising a catch component, a second component detachably receiving the catch component, a locking component mounted to turn in the second component and to slide therein transversely to the movement of the catch component into and out of locking position in the path of the catch component, the locking component having a locking surface parallel with its axis of turning movement and curved about that axis and the locking component having also a releasing surface which is backed-off from the locking surface, spring means biasing the locking component to a normal position with its locking surface opposed to the catch component and with the backed-off surface remote from the catch component, an operating member to turn the locking component from its normal position to a position in which the backed-off releasing surface is presented to the catch component to cause that component to be slid to release position by the catch component, and a cam device coaxial with said locking component and operative for moving the latter out of the path of said catch component when said locking component is turned about its axis.

30. 35. 40. 45. 17. A quick release connector comprising a catch component, a second component detachably receiving the catch component, a locking component mounted to turn in the second component and to slide therein transversely to the movement of the catch component into and out of locking position in the path of the catch component, the locking component having a locking surface parallel with its axis of turning movement and curved about that axis and the locking component having also a releasing surface which is backed-off from the locking surface, spring means biasing the locking pin to a normal position with the locking surface opposed to the catch component and with the backed-off surface remote from the catch component, an operating component to turn the locking component from its normal position to a position in which the backed-off releasing surface is presented to the catch component, and cam means to cause the turning movement of the locking component from its normal position to produce also longitudinal movement of the component to carry the locking component clear of the catch component.

18. A quick release connector comprising a catch component, a second component detachably receiving the catch component, a locking component mounted to turn in the second component and to slide therein transversely to the movement of the catch component into and out of its path of movement, the locking component having a locking surface parallel with its axis of turning movement and curved about that axis and the locking component having also a releasing surface which is backed-off from the locking surface, spring means biasing the locking component to a normal position with the locking surface opposed to the catch component and with the backed-off surface remote from the catch component, an operating component which is mounted to move rotatably about the axis of

the locking component, and means slidably and non-rotatably connecting the operating member to the locking component to enable it to be turned to present its backed-off surface to the catch component.
